MULTIPLEXING SWITCH

Carl W. Besserer, Jr., Silver Spring, Md., assignor
to the United States of America as represented
by the Secretary of the Navy

Application June 11, 1952, Serial No. 292,868

2 Claims. (Cl. 200—8)

1

The present invention relates generally to switching devices and more particularly to an improved multiplexing switch for use on a multiple subcarrier telemetering system.

The increased use of telemetering in the experimentation and development of remotely controlled aircraft has brought about an ever increasing demand for systems having greater intelligence carrying capacities. One of the factors limiting the intelligence carrying capacity of a telemetering system is the ability of the switching apparatus of the system to handle increased traffic requirements. The purpose of a multiplexing switch is to alternately apply a plurality of subcarrier signals, which are indications of the forces desired to be ascertained, to the modulator unit of a radio frequency transmitter rapidly and in sequential order. Due to the limitations of known switches, such as the speed with which switching can be attained, and the generation of noise due to chattering, etc., the number of subcarrier to signal channels usable with a single transmitter has been unduly restricted.

It is therefore one object of the present invention to provide a multiplexing switch which is capable of switching at very high speeds.

Another object of the invention is to provide a high speed multiplexing switch wherein the generation of noise within the switch is greatly reduced.

Other objects and many of the attendant advantages of this invention will be appreciated readily as the same becomes understood by reference to the following detailed description, when considered in connection with the accompanying drawings, wherein:

Fig. 1 is an axial section of the switch, partly in elevation;

Fig. 2 is an end elevation of the switch.

Referring now to Fig. 1, the multiplexing switch comprises a cylindrical casing 11 having teeth 12 projecting from its inner circumferential surface so as to form an annular internal gear 12a.

A plurality of pairs of terminals 13 project through the casing 11 at spaced intervals about the periphery of said casing and terminate in companion contacts 14 positioned in the grooves between the teeth 12 of the gear 12a. As best seen in Fig. 1, the terminals of each pair are in parallel spaced relation. These terminals 13 are secured to the casing by nuts 15.

Attached to the casing 11, as by screws 16, and supporting a cylindrical housing 17, is a

5 circular plate 18 formed with an axial opening 19. A small drive motor 21 including a driveshaft 22 is supported within the housing 18, and has its driveshaft 22 projecting through the opening 19 and axially into the casing 11. Fastened to the driveshaft 22 by a locking bolt 23 and extending radially from said driveshaft is a U-shaped bracket which defines a rotor 24 for the switch. The bracket which defines the rotor 24 10 includes legs 25 connected by a bight 26, the free ends of said legs being slotted at 27 to receive a trunnion 28 and an insulating sleeve 30 about said trunnion.

Rotatably mounted on the trunnion 28 is a 15 star-shaped contact element 29 made of conductive material and having cogs 31 which mesh with the teeth 12 of the gear 12a to bridge a companion pair of contacts of the terminals 13. Two wire springs 32 are formed with looped 20 central portions 33 which encircle the ends of the trunnion, and arms 34 bowed outwardly from each other and terminating in hooks 35, which are engageable in apertures 36 in the rotor 24. Retaining rings 37 cooperate with annular 25 grooves 38 formed in each end of the trunnion 28 to hold said trunnion, and the springs 32 in their intended positions.

In operation, each pair of terminals 13 or as 30 many pairs as there are circuits to serve, is electrically connected into its respective circuit. Upon the motor 21 being energized, the star-shaped element 26 rolls in a planetary path about the inner circumference of the casing 11. The switching action is accomplished by the cogs 31 35 which mesh with the teeth 12 of the gear 12a and sequentially short-circuit the contacts of each pair of terminals 13.

The springs 32, because of the bowed shape of 40 their arms, urge the cogs 31 of the star shaped gear 29 outwardly to firmly engage the teeth 12 of the casing 11 and thereby prevent chattering.

A switch of the type described has the unusual 45 capacity of consecutively serving a great many circuits in a short interval of time. Notwithstanding the high speed operation of the switch, chattering and other noises which are characteristic of the prior high speed switches are effectively reduced.

Obviously many other embodiments other than 50 that shown and described are possible without digressing from the teachings of the invention defined in the appended claims. For example, the cylindrical casing 11 including the gear teeth 12 may be extended to accommodate ranks of terminals in annular series each rank compris-

ing a plurality of pairs of terminals 13 and their companion contacts 14. A bank of rotor assemblies then may be arranged on a common driveshaft to accomplish the switching action. Therefore, the foregoing detailed description is to be construed only as illustrative of this invention and not as limiting upon the appended claims.

What is claimed is:

1. A multiplexing switch, comprising, an internal gear, a plurality of electric contact members disposed in the troughs of said gear, said members being insulated from each other, a driveshaft concentric with said gear, a U-shaped rotor having two legs connected by a bight and a slot formed in the extremity of each leg, said rotor being mounted on said driveshaft so that the legs extend radially from said shaft, a trunnion supported in the slots of said rotor, a star-shaped contact element rotatably mounted on said trunnion and insulated therefrom, spring means mounted on said rotor and bearing upon said trunnion to urge said contact element into firm

engagement with said gear and said contact members, and means for rotating said shaft.

2. In a multiplexing switch for sequentially closing a plurality of electric circuits, a mounting, a plurality of terminals arranged in an annularly spaced series on the mounting, and contact means engageable with said terminals, said contact means including a driveshaft, a U-shaped rotor on the driveshaft having a slot formed in the extremity of each leg of said rotor, a trunnion supported in the slots of the legs, a contact element on the trunnion, and spring means tensioned between the trunnion and the legs of the rotor for urging the contact element into selective engagement with said terminals.
